SHIPPING CONTAINER

Frederick K. Fildes, Altoona, and Lewis M. Showers, Jr., Juniata, Pa., assignors to The Pennsylvania Railroad Company, Philadelphia, Pa., a corporation of Pennsylvania

Application May 6, 1936, Serial No. 78,078

3 Claims. (Cl. 221—144)

Our invention relates to shipping containers generally and more specifically to shipping containers having bottom discharge valves.

The opening and controlling of a bottom discharge from a container is attended with considerable difficulty when the container is fully loaded or even partially loaded. The weight of the contents makes the operation of a bottom closure valve difficult. Difficulty has been experienced in controlling a bottom discharge from shipping containers both as to rate of flow and as to amount discharged. When the discharge opening is finally opened against the weight of the load, the contents are apt to force the valve further open or be discharged completely before any control can be established over the flow.

Therefore the main object of our invention is control over the rate of flow and amount to be discharged through a bottom closure valve of a shipping container. Another object is improvement in the weatherproofing of the container and the avoidance of leakage, particularly of fine materials, from the container.

Other objects and advantages will become apparent from the following detailed description of a specific embodiment of our invention, reference being had to the accompanying drawings.

Fig. I is a front view of a container having a bottom closure valve according to our invention.

Fig. II is a side view of same.

Fig. III is a section taken about the lines III—III of Fig. II.

Fig. IV is a section taken about the lines IV—IV of Fig. III.

Fig. V is a section taken about the lines V—V of Fig. I.

Fig. VI is a section taken about the lines VI—VI of Fig. III.

Fig. VII shows the subject matter of Fig. VI with the bottom closure valve open.

Fig. VIII is a perspective view of the bottom member of the container.

Fig. IX is a perspective view of a valve member.

For the purposes of a detail description the container shown in the drawings may be separated into three main parts: a container body, a bottom closure valve, and a top closure door, to be taken up in this order.

The container body is of a usual construction with side and top sheets 1 joined by frame members 2, with corner lifting hooks 3, all riveted together as shown. Riveted inside the lower part of the container body is a bottom member 4 separated into two discharge sections by a V-shaped

partition 5. This bottom member 4 which is formed in one piece, has side walls 6 and end walls 7 which slope inwardly toward the bottom discharge opening 8 of each of the sections formed by the partition 5. The partition 5 also slopes toward the openings 8 on each side.

The bottom closure valve for each discharge opening 8 comprises valve members 11 and 12, having integral supporting arms 13 at each end and strengthening ribs 15 underneath. These supporting arms 13 each have a bearing 16 formed in their upper ends by means of which they are pivotally attached to brackets 17 by pins 18. The brackets 17 at the ends of the container are fastened to the bottom member 4 by means of angle-irons 23 at the ends of the bottom member 4. At the middle of the bottom member 4 the bracket 17 is fastened to a part 19 of the V-shaped partition 5. At the ends of each valve member 11 and 12 a wall section 20 is formed to cooperate with the vertical ends of the bottom openings 8 in perfecting the closure of the valve. The discharge edges 21 and 22 of the valve members 11 and 12 respectively are rounded and beveled as shown with the edges 21 extending under the edges 22 when the valve is closed. A gasket 25 is fastened to the rib 15 to receive the edge 21, making a leak-proof and weatherproof joint. The outside edges 26 of the valve members 11 and 12 are inclined upwardly as shown in order to come into contact with gaskets 27 fastened to the outside of openings 8 which are strengthened by angle-irons 28 as shown. Thus a water-proof and weather-tight joint is provided about the closure valve when in the closed position. It is to be noted that the bottom member 4 is formed with substantially vertical surfaces outside the openings 8 in order to cooperate with the valve members 11 and 12 in making a leak-proof closure.

The operation of the closure valve is accomplished by a toggle means which is attached at each end of the valve members and which comprises operating arms 30 pivotally attached to bearings 31 of arms 13, an operating link 32 pivotally attached to the arms 30, an operating rod 33 to which each link 32 is attached by a slip fit and a weight 41 mounted on each operating link 32 to facilitate operation and maintain the open or closed position of the valve. A removable operating lever 34 is provided to fit onto the square shaped ends of the operating rod 33. The operating rod 33 is supported for rotation in brackets 35 attached to the bottom member 4. By this toggle means the strength of one man

is quite sufficient at all times to control the valve efficiently and easily.

The door 40 is mounted on top sheet 1 and is of a usual weatherproof and waterproof type 5 which is secured in place on the door frame 36 by dogs 37. A chain 38 secures the door 40 to the container when open.

The operation of the bottom closure valve is clear from the above description but a few additional comments may be of value. The operator rotates operating links 32 by rotating operating rod 33 with the lever 34 and thus opens and closes the valve. The weights 41 acting under the force of gravity urge the valve members 11 and 12 to the closed position until well open and then they urge the valve members 11 and 12 to the open position. Thus either the open or closed position of the valve is preserved. In opening the valve, the weights 41 prevent a sudden opening 20 from internal pressure and aid considerably in controlling the rate of flow and in sharply cutting off the flow at the proper moment. Thus our invention provides control of the flow from the bottom discharge of a container and at the same 25 time insures a freedom from leakage when the valve is closed. The structure is simple and economical and may easily be adapted to many standard types of containers.

While we have described an embodiment of our 20 invention in some detail above, it will be obvious to one skilled in the art that numerous changes

and variations may be made without departing from the spirit of the invention as hereinafter claimed.

Having thus described our invention, we claim:

1. In a shipping container, a bottom discharge valve comprising a discharge opening in said container, a pair of valve members pivotally attached to said container for closing said opening, said valve members having discharge edges which overlap each other in the closed position, a flange attached to the underside of the upper of said overlapping valve members and set back from the discharge edge thereof, a gasket positioned against said flange and inset from the discharge edge of the upper of said valve members to receive the discharge edge of the lower of said valve members, whereby said gasket is protected from the flow of contents from said valve. 10

2. The invention of claim 1 characterized by the further fact that the outside edges of said valve members are inclined upwardly to contact gaskets positioned outside of said opening, said gaskets being protected from the contents of said container. 20

3. The invention of claim 1 characterized further by the fact that the operation of said valve is subject to the control of a gravity influenced mechanism which facilitates the manual operation of said valve. 25
